(57) CLAIM

The ornamental design for a spa with integrated table, as shown and described.

DESCRIPTION

FIG. 1 is a perspective view of a spa with integrated table showing our new design;

FIG. 2 is a second perspective view of the spa with integrated table in an extended position;

FIG. 3 is a front elevation view thereof;

FIG. 4 is a rear elevation view thereof;

FIG. 5 is a left side elevation view thereof;

FIG. 6 is a right-side elevation view thereof; and,

FIG. 7 is a top plan view thereof.

The broken lines immediately adjacent the shaded areas represent the bounds of the claim, while all other broken lines are directed to environment and are for illustrative purposes only; the broken lines form no part of the claimed design.

1 Claim, 6 Drawing Sheets
